(57) CLAIM

We claim the ornamental design for a cab for a self-propelled bale wagon, as shown and described.

DESCRIPTION

FIG. 1 is an elevational view of the cab as seen from the left of the unclaimed self-propelled bale wagon.

FIG. 2 is an elevational view of the cab as seen from the right of the unclaimed self-propelled bale wagon.

FIG. 3 is an elevational view of the cab as seen from the front of the unclaimed self-propelled bale wagon.

FIG. 4 is a top plan view of the cab in relationship to the unclaimed unclaimed self-propelled bale wagon.

FIG. 5 is an elevational view of the cab as seen from the rear of the unclaimed self-propelled bale wagon; and,
FIG. 6 is an isometric view of the cab.

The broken line showing of the self-propelled bale wagon is for illustrative purposes only and forms no part of the claimed design.
